ABSTRACT

A multiple liquid flow proportioning system for use in reentry vehicles with transpiration cooled nose tips (TCNT). The basic system includes: a first reservoir containing coolant; a second reservoir containing the same type or a different coolant; a piston for forcing the coolant from the first reservoir and a piston for forcing the coolant from the second reservoir with both pistons integrated to form a unified structure movable in unison; and, a gas-operated mechanism to actuate the pistons and control the flow of coolants to the TCNT. The system provides for the simultaneous fluid cooling of the nose tip at high pressure and low flow rate and cooling of the nose-skirt area at low pressure and high flow rate with a single control device (e.g., valve).

3 Claims, 1 Drawing Figure

MULTIPLE FLUID FLOW PROPORTIONING SYSTEM

BACKGROUND OF THE INVENTION

This invention relates to the thermal protection of a space vehicle reentering the atmosphere, herein after referred to as a or the "reentry vehicle."

Reentry vehicles of large ballistic coefficient (i.e., small nose-cone angles) entering the atmosphere at shallow angles are subjected to long periods of flight at hypersonic velocity. Such trajectories expose the nose area of the reentry vehicle to extreme temperatures that can only be mitigated by the injection of a coolant over or through the surface to effect transpiration cooling. For a conical shaped nose tip, the flow requirements at the stagnation point, i.e., the tip, are quite different from those for the skirt area just behind the tip. By the present invention I provide a multiple liquid flow proportioning system whereby the nose region is serviced by a high pressure coolant flowing at a low rate and the skirt region is serviced by a low pressure coolant flowing at a high rate, all controlled by a single control device.

SUMMARY OF THE INVENTION

This invention pertains to a multiple liquid flow proportioning system adapted for transpiration cooling of a reentry vehicle having a conical nose section. The coolant fluid is caused to flow at different rates and pressures over and through the nose and skirt portions respectively of the nose section.

DESCRIPTION OF THE DRAWING

FIG. 1 is a side elevation view, partially in cross section, partially fragmented, and in schematic form of the preferred embodiment of the system.

DESCRIPTION OF THE PREFERRED EMBODIMENT

With reference to FIG. 1, wherein a preferred embodiment of the system is shown, there is included a conical reentry vehicle, generally designated 10, having an outer surface 11, a longitudinal axis A-B, and a fore end and an aft end, as designated by the directional arrows and the legends. The reentry vehicle 10 includes a nose section or region 12 and a skirt or side wall section or region 13 at the fore end of the reentry vehicle 10, with the skirt 13 being immediately aft of the nose 12. The nose 12 is shown in a mode detached from the reentry vehicle 10, in the interest of maintaining simplicity of the drawing.

The cooling system is physically within the reentry vehicle 10. It includes: a first reservoir 21 containing a liquid 21A for cooling the nose 12 of the reentry vehicle 10; means for directing flow of the coolant 21A from the first reservoir 21 to the nose 12, with said means generally designated with the reference numeral 22, and wherein said means 22 further includes, for example, a hollow conduit 22A passing into and through the skirt 13 and having two ends, with one end connected to an outlet in the first reservoir 21 and with the other end connected to the junction of a plurality of hollow conduits, such as 22B and 22C, which are in the nose 12 and which lead to the outer surface thereof 12A; a second reservoir 23, preferably but not necessarily located aft of the first reservoir 21, containing a liquid 23A for cooling the skirt 13 of the reentry vehicle

10; means for directing flow of the coolant 23A from the second reservoir 23 to the skirt 13, which said means generally designated by the reference numeral 24, and wherein said means 24 further includes, for example, a hollow conduit 24A passing into the skirt 13 and having two ends, with one end connected to an outlet in the second reservoir 23 and with the other end or end portion connected to a plurality of hollow conduits, such as 24B, 24C, 24D and 24E, which are in skirt 13 and lead to the outer surface thereof 12A; a first piston 25 with a head 25A having a preselected area and a second piston 26 with a head 26A and having a preselected area and also having a rear surface 26B, with said pistons 25 and 26 integrated to form a unified structure, and with said unified piston structure wholly within the reentry vehicle 10; a first chamber 27 containing a gas 27A at a preselected pressure; a second chamber 28, at a pressure lower than the preselected pressure of gas 27A, and having the second piston 26 movable within second chamber 28 and defining a portion of the second chamber 28; means for permitting the controlled flow of gas 27A from first chamber 27 to second chamber 28, with said means generally designated by and with the reference numeral 29, and wherein the means 29 further includes for example, but is not limited to, a hollow conduit 29A having two ends, with one end connected to an outlet in the first chamber 27 and with the other end connected to an inlet in the second chamber 28, and a suitable valve 29B interposed between the two ends of conduit 29A, and connected to conduit 29A, to control the flow of the gas 27A from first chamber to second chamber 28. The valve 29B is responsive to standard control means, whether of the on-board type and/or of the remote type, such as a command signal from a land-based station. None of the many available conventional valve control means is shown in FIG. 1, because said means, per se, do not form part of the invention.

Also shown in FIG. 1, by use of arrows, are: the direction of flow of the first coolant 21A; the direction of flow of the second coolant 23A; and, the direction of flow of the gas 27A from the first chamber 27 to the second chamber 28, when the valve 29B is in an open mode.

As a related matter, and with regard to the integrated and unified structure of which pistons 25 and 26 are portions, the first piston 25 is preferably disposed essentially on and perpendicular to the longitudinal axis A-B of reentry vehicle 10, although it need not be; and, it 25 is movable within, and defines a portion of, first reservoir 21. Similarly, the second piston 26 is disposed essentially perpendicularly to the longitudinal axis A-B of reentry 10; and, it 26 is movable within, and defines a portion of, second reservoir 23. Further, the first piston 25 and the second piston 26 are movable only in unison.

OPERATION OF THE PREFERRED EMBODIMENT

The operation of the preferred embodiment of the system is understood from the foregoing description, coupled with reference to FIG. 1.

Essentially the nose 12 is cooled by first coolant 21A which flows from first reservoir 21, and the skirt 13 is cooled by second coolant 23A which flows from second reservoir 23, when these fluids 21A and 23A are simultaneously forced out of their respective reservoirs 21 and 23 by integrated pistons 25 and 26 which are

moving, of necessity, in unison forwardly by the action, caused by the pressure, of gas 27A on the rear surface 26B of piston 26, as it 27A is valved from chamber 27 through conduit 29A and into chamber 28.

Since pistons 25 and 26 are moving in unison, it is 5 readily apparent that the rates of flow of coolants 21A and 23A will be proportional to the areas of the heads 25A and 26A of pistons 25 and 26. Furthermore, the pressure that there is available to coolants 21A and 23A is inversely proportional to the area of heads 25A 10 and 26A.

CONCLUSION

It is emphasized that, although there have been described and shown the fundamental and unique features of my invention as applied to a preferred embodiment adapted for a particular use, it is to be understood that various other embodiments, substitutions, additions, omissions, adaptations, and the like, will occur to, and can be made by, those of ordinary skill in the 20 art, without departing from the spirit of this invention.

I claim:

1. A multiple fluid flow proportioning system for use with a low angle reentry space vehicle of conical configuration, with said reentry vehicle having a longitudinal axis, a fore end, and an aft end, and with said reentry vehicle also having a nose and a skirt at the fore end, comprising:
  - a. a first cylindrical reservoir having a smaller diameter within said reentry vehicle and containing a 30 fluid coolant for cooling said nose of said reentry vehicle;
  - b. means for directing the controlled flow of said fluid coolant from said first reservoir to said nose of said reentry vehicle;

35

- c. a second cylindrical reservoir having a larger diameter within said reentry vehicle and containing a fluid coolant for cooling said skirt of said reentry vehicle, said second reservoir being coaxial with and spaced apart from the said first reservoir;
  - d. means for directing the controlled flow of said fluid coolant from said second reservoir to said skirt of said reentry vehicle;
  - e. a first piston movable through the first reservoir to expel coolant therefrom to the nose of the reentry vehicle;
  - f. a second piston movable through the second reservoir to expel coolant therefrom to the skirt of the reentry vehicle;
  - g. means rigidly interconnecting the first and second pistons for movement in unison;
  - h. a source of pressurized gas; and,
  - i. controlled means admitting gas from said source to one side of the second piston to move said second piston through the second reservoir whereby coolant is simultaneously expelled at a low flow rate and at a high flow rate respectively from the first and second reservoirs.
2. A system as defined in claim 1 wherein, the first piston is an elongated stem-like member attached to the second piston and cooperates with the first cylindrical reservoir to stabilize the second piston in moving through the second reservoir.
  3. A system as defined in claim 1 wherein, the source of pressurized gas is a liquified gas expanding into gaseous form in passing through the controlled means admitting gas to one side of the second piston.
